[57] CLAIM

The ornamental design for a liqueur service tray.

DESCRIPTION

FIG. 1 is a front perspective view of a liqueur service tray showing my new design, the bottom of the tray portion and the bottom of the base portion appearing plane and unornamented.

FIG. 2 is a top view thereof;

FIG. 3 is a side elevational view, the opposite side being a mirror image of the side shown therein;

FIG. 4 is an end elevational view, the opposite end being a mirror image of the end shown therein.

FIG.1.

FIG.2.

FIG. 3.

FIG. 4.
